UNITED STATES PATENT OFFICE

ALBERT L. ABBOTT, OF CANTON, OHIO, ASSIGNOR TO THE DIEBOLD SAFE & LOCK COMPANY, OF CANTON, OHIO, A CORPORATION OF OHIO

JAMB SECTION

Application filed December 14, 1925. Serial No. 75,223.

The invention relates to jambs for doors and frames therefor, and more particularly to interfitting and interlocking tongue and groove jamb sections for safes and the like for preventing the lateral spreading of the door frame away from the door when subject to intense heat and for preventing a forward displacement of the hinged door jamb from its frame jamb in the event that the safe hinges are accidentally or purposely removed or made ineffective.

Sometimes a safe door is constructed with tongue and groove jambs of one cross section which interfit and interlock with frame tongue and groove jambs of another cross section.

These different jamb sections are ordinarily made of sheet or plate material formed by dies operated by a press brake, and the necessity of providing one or more tongue and groove jamb sections for the door and one or more different interfitting and interlocking jamb sections for the door frame, thus necessitates the use of a multiplicity of dies, and consequently the use of a multiplicity of press brakes, or delays due to changing different sets of dies on the same press brake, all of which result in added cost for the finished product.

The object of the present invention is to reduce the number of dies required for making interfitting and interlocking jambs for doors and frames by providing a tongue and groove jamb section, one length of which may be used for the jamb of a safe door, and another length of which may be used for an interfitting and interlocking jamb for the door frame.

These objects are attained by the use of a jamb section, which if placed in one position with reference to a longitudinal axis of the section, and revolved about that axis 180 degrees, will interfit with another identical section placed in the original position of the revolved section.

Embodiments of the invention in use as for the interfitting and interlocking door and frame jambs of a safe are illustrated in the accompanying drawings, forming part hereof, in which—

Figure 1 is a fragmentary horizontal cross section of a safe having a door and frame constructed with the improved interfitting and interlocking jamb sections for preventing lateral spreading of the frame, and forward displacement of the hinge jamb of the door;

Fig. 2, an enlarged cross section of improved jamb sections as used for the door in Fig. 1, with dotted lines illustrating other portions of the door construction, and broken and dotted lines indicating the resulting position of the jamb sections shown in full lines, if revolved about designated longitudinal axes 180 degrees, which positions are the exact positions of lengths of the same sections when used for constructing the frame jambs as illustrated in Fig. 1.

Similar numerals refer to similar parts throughout the drawings.

An embodiment 1 of the improved jamb section for use as for the outer vertical jamb of a safe door D includes spaced, parallel walls 2, 3, 4 and 5, one edge 2" of the wall 2 being connected with one edge 3' of wall 3 by a sloping wall 6 and the other edge 3" of wall 3 being connected by the reversely extending anti-lateral-spread wall 7 with the edge 4' of wall 4 spaced between walls 2 and 3, and the other edge 4" of wall 4 being connected with one edge 5' of wall 5 by sloping wall 8 extending from wall 4 to wall 5 in the same general direction that wall 6 extends from wall 2 to wall 3, wall 5 being spaced beyond walls 4 and 3 so that wall 3 is spaced between walls 4 and 5.

The jamb section as best illustrated in Fig. 2, may be a right horizontal cross-section of a length of jamb section whose walls are perpendicular to the plane of the drawing and having wall edges all parallel with each other.

If the section 1 be revolved about a longitudinal axis O, perpendicular to the plane of the paper and therefore apparent as a point, 180 degrees from the reference line X—X, in the direction indicated by the broken arrow headed arcs a, b, c, d, e, f, g and h, the section would then occupy the position indicated by the dotted lines at 1'.

In other words a length of section identical to the length 1 for the door jamb, if positioned as indicated by the dotted lines 1', may be used as an interfitting and interlocking frame jamb for the section 1.

The proportions of the walls of the improved jamb section 1 are such that walls 6, 3 and 7 constitute protruding tongues which interfit and interlock with the retreating groove formed by walls 7, 4 and 8, of a length of the same section when placed in the position indicated at 1', and it is obvious that the anti-lateral-spread wall 7 of the frame jamb will abut the wall 7 of the door jamb, if the frame is caused to expand laterally by heat or other forms of energy, and that the greater the tendency to expand, the tighter will be the lateral abutment of walls 7.

A modified jamb section 10 may be used for the hinge-side vertical jamb of the safe door, and includes spaced walls 12, 13, 14 and 15, one edge 12'' of the walls 12 being connected with one edge 13' of wall 13 by an anti-forward displacement wall 16 and the other edge 13'' of wall 13 being connected by the reversely extending anti-lateral-spread wall 17 with the edge 14' of wall 14, and the other edge 14'' of the wall 14 being connected with one edge 15' of wall 15 by anti-forward displacement wall 18, and wall 12 being provided at its edge 12' with an angled leg 12^a, and wall 15 being likewise provided at edge 15'' with an angled leg 15^a.

The jamb section 10 as best illustrated in Fig. 2 may be as aforesaid a right horizontal section of a length of jamb section whose walls are perpendicular to the plane of the drawing and having wall edges all parallel with each other. If the section 10 be revolved about an axis O' perpendicular to the plane of the paper and therefore apparent as a point 180 degrees from the reference line X'-X', in the direction indicated by the broken arrow headed arcs j, k, l, m, n, o, p, q, r and s, the section would then occupy the position indicated by the dotted lines at 10'. In other words a length of section identical to the length 10 for the door jamb, if positioned, as indicated by the dotted lines at 10' may be used as an interfitting and interlocking frame jamb for the section 10. The proportions of the walls of the improved jamb section 10 are such that walls 16, 13 and 17 constitute protruding tongues which interfit and interlock with the retreating grooves formed by walls 17, 14 and 18 of a length of the same section when placed in the position illustrated by the dotted lines at 10', and it is obvious that the anti-forward displacement walls 16 and 18 of the frame jamb will abut the walls 18 and 16 of the door jamb, if some form of energy causes a forward displacement of the door jamb 10, after or coincidental with the removal or damage of the hinges; and likewise the walls 17 will prevent lateral spreading of

the frame from the door, separately or simultaneously with any tendency to forward displacement thereof.

Referring now more particularly to Fig. 1, the safe door D may be constructed in a usual manner with outer plate 20 spaced from inner plate 21. Edges 20' and 21' of the plates may be secured as by welding to the wall 2 and the edge 5'' of the outer jamb section 1 and edges 20'' and edges 21'' may be secured as by welding to the angled legs 12^a and 15^a of hinge side jamb section 10, forming vertically extending closed polygonal walls for a safe door whose enclosed space S may be filled with a suitable heat resisting insulation.

The door thus formed may be hinged as at 22 with the upright side wall 23 of a safe which includes an outer case angle 24 connected as by welding with the edge 25 of an inner compartment side wall 26 by a length of improved tongue and groove door frame jamb section positioned as at 10' as aforesaid, interfitting and interlocking with the other length 10 of the same identical section as aforesaid.

The opposite side wall 27 of the safe likewise includes outer case corner angle 28 connected as by welding with edge 29 of inner compartment side wall 30 by the length of door frame jamb section placed as aforesaid as indicated at 1' and being as aforesaid identical to the length 1 of the same section used for the door jamb and positioned for interfitting and interlocking therewith.

The top and bottom door jambs and interfitting and interlocking frame jambs therefor, not shown, may preferably be made of lengths of the jamb section 1 for preventing vertical lateral spreading as aforesaid.

I claim:

1. A safe including a door frame and a door, the door frame including a jamb member and the door including another jamb member, the jamb members interfitting and interlocking with each other for preventing lateral deflection of the door frame, and each jamb member having identical cross-sections.

2. Interfitting and interlocking tongue and groove jamb members for safe door frames and doors and the like, each member including spaced parallel walls connected by sloping walls and an anti-lateral deflection wall to form a tongue and a groove for interfitting with the groove and tongue of the other member, and each member having the same cross-section.

3. Interfitting and interlocking tongue and groove jamb members for safe door frames and doors and the like, each member including spaced walls connected by sloping walls and anti-forward displacement walls to form a tongue and groove for interfitting with the groove and tongue of the other member, and each member having the same cross-section.

4. Interfitting and interlocking tongue and
groove jamb members for safe door frames
and doors and the like, each member includ-
ing spaced walls connected by an anti-lateral
5 deflection wall and anti-forward displace-
ment walls to form a tongue and groove for
interfitting with the groove and tongue of
the other member, and each member having
the same cross-section.

10 In testimony that I claim the above, I
have hereunto subscribed my name.

ALBERT L. ABBOTT.
